UNITED STATES PATENT OFFICE.

DOMINICK DREIER, OF LIVINGSTON, MONTANA.

HEATING PLANT.

1,235,126.

Specification of Letters Patent. Patented July 31, 1917.

Application filed June 26, 1916. Serial No. 105,983.

To all whom it may concern:

Be it known that I, DOMINICK DREIER, a citizen of the United States, residing at Livingston, in the county of Park and State of Montana, have invented a new and useful Heating Plant, of which the following is a specification.

The device forming the subject matter of this application is a steam heating plant, and one object of the present invention is to provide a structure of this type through which the steam will find its way in a minimum amount of time.

Another object of the invention is to provide a steam heating plant in which air valves located adjacent the radiators may be dispensed with, thereby avoiding any possibility of damage to floors, carpets, ceilings and the like, caused by water and steam spouting out of the air valves on the radiators.

Another object of the invention is to provide novel means whereby the water of condensation derived from the steam will be forced back into the boiler.

Another object of the invention is to provide novel means whereby, although an adequate and efficient outlet for air is provided, no air will be sucked back into the steam circulatory system when the pressure therein falls.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings:

Figure 1 is a diagram in the nature of a vertical elevation, showing a steam heating plant constructed in accordance with the present invention;

Fig. 2 is a sectional view showing the separating tank and adjacent parts, the same

being disposed in the positions which they will assume while air is escaping; and

Fig. 3 is a view similar to Fig. 2, but showing the parts in the positions which they will assume while the air outlet is closed, and while water of condensation is being forced back to the boiler.

In the accompanying drawings, the numeral 1 indicates a radiator and the numeral 2 denotes a boiler. At 3 there appears a separating tank equipped with an upstanding neck 4 having a lateral outlet 5, the neck 4 being provided with guides 6. At the top of the separating tank 3 there is formed a seat 7. A stem 8 is mounted to reciprocate vertically in the guides 6 and carries a valve 9 coöperating with the seat 7. Attached to the lower end of the stem 8 and located within the tank 3 is a float 10.

A water return conduit 11 leads from the separating tank 3 to the boiler 2. In the water return conduit 11 is located a check valve 12 which closes toward the separating tank 3. Leading from the boiler 2 is a delivery pipe 14 connected with one side of the radiator 1, the delivery pipe being extended as shown at 15, so that as many radiators as desired may be provided. Leading from the radiator 1 is a return pipe 16 which communicates with the boiler 2. The pipe 16 is prolonged as shown at 17, so as to accommodate more than one radiator.

Branched off from the return pipe 16 and leading to the separator tank 3 is an air pipe 18 in which is interposed a thermostatic valve 19. The valve 19 is constructed to permit the passage of air and water, but is adapted to close when steam traverses the air pipe 18. There are many thermostatic valves of this kind, and I do not claim to have invented this thermostatic valve *per se*. Interposed in the air pipe 18 between the thermostatic valve 19 and the point 21 where the pipe 17 joins the pipe 16 is a check valve 20 which opens toward the separator tank 3 and closes in an opposite direction.

Let it be supposed that the pressure in the boiler 2 is comparatively low and that the boiler is being fired up. Under such circumstances, the major part of the water of condensation returns to the boiler 2 by way of the pipe 16, while the air and a small

part of the water of condensation traverse the pipe 18, the valve 20 opening and the thermostatic valve 19 permitting the air and the water of condensation (if any) to enter 5 the separating tank 3, the water passing to the bottom of the separating tank, and the air passing through the outlet 5. The amount of water of condensation delivered to the separating tank 3 will depend on the 10 pressure in the boiler 2 and upon the relative vertical positions of the pipes 17 and 18, it being understood that Fig. 1 of the drawings is diagrammatic, to a considerable extent, so far as the relative positions of the 15 pipes 17 and 18 are concerned. In any event, the air in the piping will be conducted away, and whatever quantity of water of condensation happens to traverse the pipe 18 will be received in the separating tank 3. 20 When steam traverses the air pipe 18 and comes into contact with the thermostatic valve 19, the latter closes, and consequently, steam cannot flow out through the separator tank 3 and its outlet 5. 25 After a time, a considerable amount of water will accumulate in the separator tank 3, as shown in Fig. 3. The float 10 then disposes the valve 9 against the seat 7, and the air outlet 5 is sealed. The air pressure within 30 in the separator tank 3 then will force the accumulated water in the tank 3 back to the boiler 2 by way of the pipe 11, the valve 12 opening to permit such an operation. The valve 12 prevents water from being forced 35 back from the boiler 2 into the separating tank 3, and the valve 20, closing away from the separator tank 3 and toward the radiator 1, prevents air from being drawn into the radiator 1 and the piping system, when 40 the pressure within the boiler 2 falls. It is to be noted that, in the absence of the

valve 20, air might be drawn into the air outlet 5 when the valve 9 is depressed as shown in Fig. 2.

The device forming the subject matter of 45 this application not only renders unnecessary, air outlet valves on the radiators, but, as well, enables the steam to work through the structure quickly.

Having thus described the invention, what 50 is claimed is:—

In a steam heating system, a radiator; a boiler; a separating tank having an air outlet; a valve controlling the air outlet; a float rigidly assembled with the valve and 55 disposed within the separating tank; a single water return conduit leading from the separating tank to the boiler; a check valve in the conduit and closing toward the separating tank; a delivery pipe leading from 60 the boiler to the radiator; a thermostatic valve mounted directly on the tank and constructed to permit the passage of air and water, but adapted to close when steam enters the valve; a return pipe leading from 65 the radiator to the boiler; a single air pipe leading from the return pipe to the thermostatic valve; and a check valve in the air pipe, and independent of the float, the last specified check valve being located between 70 the thermostatic valve and the point of juncture between the air pipe and the return pipe, the said check valve opening toward the separating tank.

In testimony that I claim the foregoing 75 as my own, I have hereto affixed my signature in the presence of two witnesses.

DOMINICK DREIER.
